ATTORNEY

GRATE FOR INDUSTRIAL FURNACES

BACKGROUND OF THE INVENTION

The present invention relates to grates, more particularly to improvements in grates used for the removal of waste material from large industrial furnaces. Still more particularly, the invention relates to improvements in grates which employ a combination of grate components at least one of which is movable to effect such removal.

For example, a presently known construction embodies a fixed grate element and a movable final discharge or conveying element, there being an aperture between the two elements to allow clearance for the discharge element to move. During the heat treatment of the material that passes through the furnace ashes, cinders, slag or scale which develop in connection with such heat treatment are deposited on an initial grate element and are transferred by mechanical means to the fixed grate element whereupon the waste material is further deposited onto the movable discharge element which discharges the waste into a discharge chute.

A disadvantage inherent in this type of grate construction is that some waste material often falls into the aperture in front of the discharge element, rather than onto the discharge element.

SUMMARY OF THE INVENTION

It is an object of this invention to provide a novel grate means for removing waste material from large industrial furnaces.

Another object of this invention is to eliminate the drawbacks of presently known grates used to remove waste material from large industrial furnaces through the use of a continuous grate of improved design and construction.

Another object of this invention is to provide a grate which efficiently controls the transport of waste material in large industrial furnaces.

The improved grate comprises a first grate member, a driven second grate member which defines a gap with the first member and a third grate member which bridges the gap between the first and second members. The third grate member is movable with reference to the first and second members and abuts the second member.

The novel features which are considered as characteristic of the invention are set forth in particular in the appended claims. The improved grate itself, however, both as to its construction and its method of operation, together with additional features and advantages thereof, will be best understood from the following description of specific embodiments when read in connection with the accompanying drawing.

BRIEF DESCRIPTION OF THE DRAWING

The single FIGURE is a schematic sectional view of a preferred embodiment of the present invention.

DESCRIPTION OF THE PREFERRED EMBODIMENTS

Referring to the single FIGURE there is shown a first grate member, grate bar 1, a second grate member, discharge drum 2, which defines a gap with the first member, and a third grate member, intermediate grate bar 5 which bridges the thus formed gap. Furnace frame 9 includes as a part thereof a support means for bar 5 shown by pivot 3. One end of bar 5 is articulately connected to the pivot 3, which has a horizontal axis, in such a manner that bar 5 is movable in a vertical direction which is substantially normal to the axis of pivot 3. The other end of bar 5 is in the form of a rounded portion 4 which abuts against the external surface of drum 2. Drum 2 is driven to rotate about an axis which is substantially parallel to the axis of pivot 3 in a direction indicated by the arrow by means of shaft 10 which is coupled to a not shown prime mover. The external surface of drum 2 comprises a series of projections or ripples 8. As drum 2 is rotated in the direction shown, end portion 4 of bar 5 bears against the surface of

drum 2 at a point above the axis of drum 2 by reason of the weight of bar 5. Bar 5 follows the contour formed by ripples 8 in a manner analogous to that of the movement of a cam and follower. Thus ripples 8 on drum 2 impart periodic motion to bar 5 causing it to move in an oscillatory manner about pivot 3 while it remains in constant sliding contact with the surface of drum 2 in the region where such surface travels upwardly.

This arrangement of intermediate bar 5 between grate bar 1 and drum 2 forms a continuous path for the transfer of waste material practically without apertures or spaces between these components. A significant advantage of this construction is that by eliminating the gaps between the components, the waste material such as ashes, cinders, slag or scale can be transferred in a more efficient manner than has been possible with presently known grate constructions. This is because whatever clearances may still exist between the individual components do not allow an appreciable amount of waste material to pass through. It is possible to further reduce the likelihood of material loss between the grate members 1 and 2 by adding a biasing means to control the contact pressure of bar 5 against the peripheral surface of drum 2. For example, and as shown in the drawing, the biasing means can include a connecting member 6 which is pivotally connected to bar 5 as shown at 6a, while the other end is resiliently mounted to frame 9 by means of an adjustable spring means 7. By varying the biasing force of spring means 7, the tension of member 7 acting upon bar 5 can be increased or decreased, thereby varying the contact pressure of bar 5 against drum 2 in addition to or detraction from the already existing contact pressure which results from the weight of bar 5.

The present invention serves to provide a number of advantages over the prior art in that:

1. The waste material is efficiently transported to a predetermined location to the right of drum 2 in the FIGURE.
2. The waste material cannot fall between grate members 1 and 2 even though there may be a substantial gap between them.
3. The accumulation of waste material can be more easily controlled to ensure that there will be no interference with the rotation of drum 2.
4. The novel intermediate grate bar 5 does not interfere with the rotation of drum 2, despite the fact that bar 5 bridges the gap between grate members 1 and 2.
5. Rotation of drum 2 can be utilized to impart periodic motion to bar 5 and thereby aid in the efficient transfer of material from bar 1 to drum 2.
6. Such efficient transfer of the waste material is facilitated by the fact that the upper sides of grate bars 1 and 5 slope respectively downward toward grate bar 5 and drum 2.

Without further analysis, the foregoing will so fully reveal the gist of the present invention that others can, by applying current knowledge, readily adapt it for various applications without omitting features which fairly constitute essential characteristics of the generic and specific aspects of the above-mentioned contribution to the art.

I claim:

1. A grate, particularly for use in large industrial furnaces, comprising a first grate member; a driven second grate member having an axis and a surface about said axis and being rotatable in one direction about said axis, said second grate member defining a gap with said first grate member; a third grate member bridging the gap between said first and second members, said third grate member being movable with reference to said first and second members and abutting said surface of said second member during rotation of the latter about its axis.
2. A grate as defined in claim 1, wherein said rotatable second grate member comprises a drum rotatable about a substantially horizontal axis, said third grate member abutting with one end thereof against the peripheral surface of said drum and being mounted at the other end thereof for pivotal movement about an axis substantially parallel to said drum axis.

3. A grate as defined in claim 2, wherein said one end of said third grate member is rounded.

4. A grate as defined in claim 2, wherein said third grate member bears by gravity against said second grate member.

5. A grate as defined in claim 2, further comprising support means for said third grate member.

6. A grate as defined in claim 5, further comprising a frame including said support means, said support means comprising a pivot having a substantially horizontal axis.

7. A grate as defined in claim 6, wherein said third member has an end portion articulately connected to said pivot and movable in a direction which is substantially normal to said axis.

8. A grate as defined in claim 2, further comprising means for imparting periodic motion to said third grate member.

9. A grate as defined in claim 8, wherein said means for imparting periodic motion to said third grate member comprises

projections on the external surface of said second grate member.

10. A grate, particularly for use in large industrial furnaces, comprising a first grate member; a driven second grate member defining a gap with said first member; a third grate member bridging the gap between said first and second members, said third grate member being movable with reference to said first and second members and abutting against said second member; and biasing means for urging said third grate member against said second grate member.

11. A grate as defined in claim 10, wherein said biasing means comprises a connecting member secured to said third grate member, a frame, and resilient means operating between said frame and said connecting member to urge said third member against said second member.
